CIVIL WAR

Letters, Diaries, Manuscripts, Etc.

John C. Frémont

The following is a copy of the following Patent, now a making part of the same, containing a description in the words of the said inventor Clark himself of his Bag-Boat.

Make a raft of timber of any dimensions suitable to the object in view, broad upon its sides and ends of a thickness sufficient, if required, to resist a cannon-ball, and divide the whole into two, five feet more or less. The timber is supposed to be placed at parallel distances in the two and locked together, firmly, so as to prevent the float resembling a chest without a lid, with a bottom of ruled timbers and a top piece covered with sides and ends of a firm and close texture. Within this float, place with goods or vessels, as rum, powder, &c., either with or without a fated bottom, rising & falling with the increase or decrease of the space occupied by the goods, or empty vessel. Then cover the chest or float with a firm deck effectively secured by connection with the bottom, so as to answer the purpose of having any means of defense. The chest may consist of pumice-stone, pipes or other empty vessels, such as may appear most proper for the particular object in view. It is to be observed that the bottom may be varied in shape from the chest, to resemble a boat, ship &c. at pleasure, and this application of the principle of buoying bottoms by empty vessels in these inclosures may be extended as well to sustaine machinery, mills, to convey burdens in shallow water and along rivers, and to a variety other purposes, as to sustain boats. On the top of the float may be created a foot of any reasonable dimensions required, and the buoyant principle is such, that it is confidently asserted that it may be made to support all the means of

of your favor and trust you will do the same. I have a good many
standards to float for up there to place, and as you will
be needed in the cabin to help get the traps off you will be
by water, and to put back damage effects.

Yours

John C. Clark
Joseph C. Clark

Edward Clark.
